PROCESS OF AND BLANK FOR USE IN MAKING SLIDERS FOR SEPARABLE FASTENERS

Filed April 22, 1927

UNITED STATES PATENT OFFICE

GEORGE E. PRENTICE, OF BERLIN, CONNECTICUT

PROCESS OF AND BLANK FOR USE IN MAKING SLIDERS FOR SEPARABLE FASTENERS

Application filed April 22, 1927. Serial No. 185,875.

This invention pertains to separable fasteners of that general type of which an earlier example is disclosed in the patent to Judson, No. 504,038, August 29, 1893, and relates more particularly to a novel process of making sliders of the type claimed in my copending application Serial No. 185,874 filed April 22, 1927, and to a blank useful in the practice of said process.

10 The most common form of slider employed in fasteners of this type has spaced front and rear wings united at one end, the opposite faces of the wings having cam-like elements for guiding the opposed series of fasteners as they approach or recede. Certain attempts have been made to form such sliders by a die casting or similar process with the object of securing a rigid and durable construction, (the British patent to Kuhn-Moos, No. 20 14,358, January 19, 1912, apparently disclosing one example of this form of slider) but as this mode of procedure is expensive and difficult and the resulting slider is often unduly heavy and clumsy looking, sliders 25 formed in this manner have not found favor, at least in this country.

The usual form of slider is made of sheet metal for the sake of lightness and ease of manufacture, but in order to obtain the necessary stiffness to withstand the strains to which it is subjected it is substantially necessary to provide some type of reinforce to stiffen the slider, particularly at the neck or narrow part which unites the front and rear 30 wings, so as to hold the wings in parallel relation and to prevent them from spreading or twisting. Heretofore it has been customary to make the reinforce member or yoke from one or more pieces of sheet metal, independent of the slider proper (that is to say the wings with their connecting neck) and then, after bending or otherwise shaping the various parts, to assemble them and connect them by suitable fastening means, for example, rivets or solder. To prepare these several independent parts, to assemble them, and then to connect them necessitates the employment of several dies (for blanking, bending, etc.),—the careful assemblage by hand of a plurality of minute parts, and the

riveting or other operation necessary permanently to unite them, and this long series of operations consumes time and an unnecessary amount of material and unduly increases the cost of production. Since the complete 55 fastener including the slider must be manufactured to sell at a low price, it is essential to keep the cost of producing the slider as low as possible consistent with the production of an article of good quality. 60

In accordance with the present invention I have devised a novel process of making sliders together with a blank useful in the practice of the process by means of which the cost of material and labor employed in producing 65 sliders of this type is reduced to a minimum, while at the same time the resulting slider possesses all of the characteristics which are to be desired in a slider, that is to say, light weight, pleasing appearance, stiffness, durability, and ease of operation. This improved slider consists of but a single piece of sheet metal (not including the handle or pull device) so shaped and bent as to provide the front and rear wings with their connecting 70 neck, the stiffening or reinforce member, a pull attaching element, and also such securing means as are necessary to hold the parts permanently in proper relation. 75

In the accompanying drawings I have illustrated by way of example certain forms of blank useful in performing my improved process, together with certain of the more important steps in the process as well as the novel slider resulting from the practice of 80 this process. In the drawings 85

Fig. 1 is a fragmentary front elevation showing a fastener of the general type above referred to, provided with a slider constructed in accordance with the present invention;

Fig. 2 is a side elevation from the left-hand side of the slider shown in Fig. 1, removed from the fastener elements;

Fig. 3 is a vertical section substantially 95 on the line 3—3 of Fig. 2;

Fig. 4 is a vertical section partly in elevation substantially on the line 4—4 of Fig. 1 showing the slider removed from the series of fastener elements; 100

Fig. 5 is a vertical section substantially on the line 5—5 of Fig. 4;

Fig. 6 is a bottom plan view of the slider, omitting the pull device;

Fig. 7 is a transverse section substantially on the line 7—7 of Fig. 5;

Fig. 8 is a rear elevation of the complete slider;

Fig. 9 is a plan view of a one-piece blank adapted to form the entire slider body, exclusive of the pull device;

Fig. 10 is a view of the blank shown in Fig. 9 but after the earlier steps of the operation of forming the slider have been completed;

Fig. 11 is an edge elevation of the blank showing its appearance after it has been subjected to certain subsequent operations;

Fig. 12 is a side elevation of the blank showing it at a further stage of the process;

Fig. 13 is a side elevation of the blank showing it just prior to completion of the slider;

Fig. 14 is a fragmentary plan view showing a modified construction of the upper end 25 of the blank shown in Fig. 9;

Fig. 15 is a fragmentary view illustrating a modified construction of the lower end of the blank shown in Fig. 9; and

Fig. 16 is a bottom plan view showing the slider embodying the modifications shown in Figs. 14 and 15 together with other slight modifications.

In Fig. 1 the numerals 1 and 2 designate a pair of tapes or "stringers" to whose opposed edges the series of fastener elements 3 and 3^a are secured. As here shown, these fastener elements are of the general type disclosed in my copending application Serial No. 709,643, April 28, 1924, the fastener elements of each series constituting the individual turns of spiral coils of wire, the turns of one coil being hooked and adapted to intermesh between the turns of the opposite coil and positively to interlock therewith in the manner fully described in my aforesaid copending application.

The form of slider disclosed in Figs. 2 to 13 inclusive is particularly adapted for use with fastener elements of the above character, but, if desired, I may employ fastener elements of other types, for example, such as shown in the copending application of Prentice and Legat, Serial No. 91,932, March 13, 1926, in which the fastener elements of both series are alike. For use with fastener elements of this latter character I prefer to employ a slider of the modified construction shown in Fig. 16 as will be described more fully hereafter. However, it is to be understood that so far as the broad principles of the present invention are concerned it is immaterial as to the specific type of fastener element with which the slider is to cooperate.

As here illustrated my improved slider 65 comprises substantially parallel spaced front

and rear wings 4 and 5 respectively united by a relatively narrow neck portion 6 and in these respects resembling in general the type of slider disclosed in the patent to Judson No. 788,317, dated April 25, 1905.

In preparing my improved slider I preferably proceed by first blanking out from sheet metal or other material of a suitable thickness a blank of substantially the shape shown in Fig. 9. This blank comprises the wide upper part 4^a which is adapted to form the front wing 4 of the slider, united by the relatively narrow part 6 which forms the neck of the slider, to the wide part 5^a designed to form the rear wing 5 of the slider as above described. When the slider is to be employed with fastener elements of the type shown in Fig. 1, I prefer to provide only the front wing 4 with inturned marginal guide flanges. To provide these flanges I form that portion 4^a of the blank which is to make the front wing somewhat wider than the part 5^a which is making the rear wing and by bending the blank along lines 7^a and 8^a in Fig. 10, I produce the guide flanges 7 and 8.

The flanges 7 and 8 constitute the outer guiding walls of the usual channels of the slider, and I preferably form the inner walls of these channels by providing the neck 6 with laterally extending tabs 9^a and 10^a which may be bent along their lines of union with the neck proper so as to form the inner guiding elements 9 and 10, as indicated in Fig. 3, for example.

I provide openings 11 and 12 in the parts 4^a and 5^a at points spaced from but adjacent to the neck 6 and I also preferably provide an aperture 13 adjacent to the free end of the part 4^a.

The free or lower end of the wing portion 5^a of the blank is provided with an extension 14 adapted to constitute the reinforce member of the slider, and certain other parts to be described. This extension or reinforce member 14 is preferably of more or less lozenge shape and is provided with a central opening 15, preferably of diamond or generally similar shape. This opening thus divides the extension 14 so as to form the spaced strip-like portions 16 and 17 which diverge from each other and which are united at their ends to the strip-like portions 18 and 19 spaced from each other and which converge and unite at their lower ends. I provide inwardly directed tabs 20 and 21 extending into the opening 15 from the opposite edges thereof and substantially at the widest portion of the opening. Preferably these tabs incline downwardly and converge toward each other as shown in Fig. 9 for a purpose hereinafter to be described.

The lower ends of the strip members 18 and 19 merge into a relatively narrow part 22 (whose width is substantially equal to the combined widths of the parts 18 and 19) and,

as shown in Fig. 9, the part 22 is provided at its end with a tongue 23 which is adapted, in the completed slider, to extend through the opening 13 at the free end of the front wing 4.

Having prepared the blank in this manner 5 the marginal edges of the wing 4 may be turned in as above described to form the flanges 7 and 8 and the tabs 9^a and 10^a are likewise bent to form the inner guide elements; these parts being shown as thus bent 10 out of the plane of the blank in Fig. 11. Either before, after, or simultaneously with this operation, in which the guiding elements are bent, I may bend the tabs 20 and 21 at 15 substantial right angles to the plane of the blank and in the opposite direction from the flanges 7 and 8, as shown in Fig. 11. I also bend the part 22 along a line such for example as indicated at 24 in Fig. 10, so that 20 its lower end is at right angles to the plane of the blank, as also shown in Fig. 11.

The next operation is to contract the extension portion 14 laterally so as substantially to close the opening 15, thus bringing the 25 edges of the members 16 and 17 substantially into contact,—the edges of the parts 18 and 19 substantially into contact, and the tabs 20 and 21 into engagement. During this contraction of the extension 14, the metal flows 30 or draws to such an extent that the tongues or tabs 20 and 21 assume the position shown in Fig. 11 in which they register with each other and stand at right angles to the face of the blank. The blank is now bent along the 35 lines of union of the neck 6 with the respective wing portions 4^a and 5^a so as to bring the latter into substantially parallel relation to constitute the front and rear wings 4 and 5 respectively of the completed slider. 40 This bending brings the openings 11 and 12 into substantial alignment.

I next bend the blank back along the line 14^a (which is substantially at the junction of the wing 5 with the extension 14) so as to 45 cause the parts 16 and 17 to lie substantially in contact with the outer face of the wing 5. As the parts are brought into this position, as indicated in Fig. 12, the tongues or tabs 20 and 21 pass through the openings 12 and 11 50 of the rear and front wings (such openings being in alignment) until the forward ends of the tongues 20 and 21 project, as shown in Fig. 12, beyond the front face of the front wing 5. I now bend these forwardly projecting ends of the tongues or tabs 20 and 21 55 preferably in opposite directions, as indicated in Figs. 5 and 7, to cause them to lie substantially flat against the front face of the front wing. If desired, I may secure these forwardly projecting ends of the tabs to the wing by means of solder or otherwise, although bending is simpler and the use of solder is not usually necessary. The tongues 20 and 21 thus arranged constitute a rivet 60 elongate in the direction of the axis of the

slider and exemplifying connecting means uniting the wings at a point spaced from but preferably adjacent to the neck 6 and adapted to stiffen the wings and to prevent them from spreading when subjected to the strains incident to use. If desired, either before or after the tongues or tabs 20 have been passed through the openings in the wings, I may bevel the lower edges of these tongues or tabs, as shown at 20^x in Fig. 3. Such beveling may be desirable since the tongues 20 and 21 not only act collectively as a rivet or connecting element, but they also function as a separator or guide, cooperating with the inturned tabs 9 and 10 to define the guide channels for the opposed series of fastener elements. As indicated in Fig. 3 the tongues or tabs 20 and 21 are disposed between the lower ends of the guiding elements 9 and 10 so that these several elements in combination 80 constitute a more or less wedge-shaped structure at the central part of the slider body adapted in well known manner to cooperate with the fastener elements as the latter are brought into engagement or are 85 separated by the operation of the slider.

After the forward ends of the tongues or tabs 21 and 20 have been turned outwardly or otherwise secured, as above described, I next bend the blank along a line such as indicated at 14^b, Fig. 10, so as to cause a portion of the blank to overlie the upper surface of the neck 6, as indicated at 25 in Figs. 2 and 4. I now again bend the blank as along the line 14^c (Figs. 10 and 13) so as to cause the portions 18 and 19 to lie substantially parallel to the front wing 4. Preferably the bend 14^c is at such a point that the parts 18 and 19 are spaced from the front surface of the wing 4, such parts 18 and 19 thus constituting a 100 loop which is adapted to enter an opening 27 in the pull device 28. At this stage in the operation the pull device may be threaded over the end 23 of the blank, and after being 105 properly positioned upon the parts 18 and 19, the end portion 22 of the blank with its tongue 23 is pressed inwardly toward the wing 4 until the tongue 23 passes through the opening 13. The end of the tongue 23 may then be turned over against the inner surface of the front wing or may be upset or 110 secured by solder or in any other desired manner.

The fastener thus constructed, with the exception of the pull device, consists of a single 115 unitary piece of sheet material comprising the front and rear wings, the neck, the inner and outer guiding elements, the rivet for uniting the wings, and the retainer for the pull device, and as this single piece of material may be blanked out from a sheet at a single operation and requires but simple operations for reducing the blank to the form of a completed slider, it is evident that it may 120 be constructed at a minimum cost and by the 125 130

employment of relatively unskilled labor. At the same time this slider possesses all of the desired characteristics of a commercial form of slider, being light in weight, thin in a front to rear direction, stiff and durable, and capable of working smoothly in cooperation with the opposed series of fastener elements.

In Figs. 14, 15 and 16 a slight modification is shown, the upper end 4^b of the blank being indicated as provided with an extension 29 having tabs 30 projecting from its end. The lower end 22^a of the extension member is shown as provided with notches 28 in its opposite edges but without the tongue 23 above described. In assembling the parts and after the slider elements have been brought substantially into the position shown in Fig. 13, the tabs 30 are inserted in the notches 28 and are then bent or pressed inwardly, as indicated in Fig. 16, thus firmly uniting the parts to one another. In Fig. 16 I have shown the front plate provided with the marginal flanges 7^b and 8^b and I have also shown the rear plate as provided with marginal flanges 7^c and 8^c, this construction being particularly adapted for use with fastener elements of the general type shown in the British patent to Kuhn-Moos above referred to or in the copending application of Prentice and Legat No. 91,932, March 3, 1926, but so far as the broad invention is concerned it is immaterial whether the slider be provided with marginal flanges upon one or both wings.

Having thus described a preferred mode of procedure or process of producing sliders of improved construction, together with certain forms of blank useful in the practice of such process, and with the understanding that the above process is susceptible of variations in respect to the order of steps, the number of steps, and the particular steps employed, and that the process is not necessarily confined to the specific shape of blank herein described, but that the various steps and the particular order of such steps hereinabove described, as well as the shape of the blank, are merely illustrative and not restrictive of the invention.

I claim:

1. That process of making a slider of the class described which comprises as steps preparing a sheet metal blank having parts shaped appropriately to constitute front and rear wings, a neck, and a flat rivet member, bending the blank at the junctions of the neck and wings to bring the wings into substantially parallel relation, disposing the flat surface of the rivet member in a plane which is substantially perpendicular to the wings and parallel to the longitudinal axis of the slider, and causing the rivet member to unite the wings at a point spaced from the neck.

2. That process of making a slider of the

class described which comprises as steps preparing a unitary sheet metal blank having parts shaped appropriately to constitute front and rear wings, a neck, and a flat rivet member, bending the blank at the junctions of the neck and wings to bring the wings into substantially parallel relation, disposing the flat surface of the rivet member in a plane substantially parallel to the axis of the slider and in such a position relative to the wings and neck as to adapt it to serve as a separator guide for cooperation with opposed series of fastener elements, and causing the rivet member to unite the wings.

3. That process of making a slider of the class described which comprises as steps preparing a unitary blank of sheet metal having parts shaped appropriately to form front and rear wings, a neck, and a reinforcing strip, and bending the blank to bring the wings into substantially parallel spaced relation and to cause the reinforce strip to assume a U-form embracing the neck and the wing members between its arms.

4. That process of making a slider of the class described which comprises as steps preparing a blank consisting of a unitary piece of sheet metal having front and rear wings united by a relatively narrow neck and having a reinforce portion united to one of the wings, bending the blank to bring the wings into substantially parallel relation and bending the reinforce portion of the blank to cause it to lie substantially in contact with the outer surface of the wing with which it is united and to embrace the neck.

5. That process of making a slider of the class described which comprises as steps preparing a blank consisting of a unitary piece of sheet metal having front and rear wings united by a relatively narrow neck and having a reinforce portion united to one of the wings, bending the blank to bring the wings into substantially parallel relation, and bending the reinforce portion of the blank to cause it to lie substantially in contact with the outer surface of one wing and substantially to conform to the outer surface of the neck.

6. That process of making a slider of the class described which comprises as steps preparing a blank consisting of a unitary piece of sheet metal having front and rear wings united by a relatively narrow neck and having a reinforce portion united to one of the wings, bending the blank to bring the wings into substantially parallel relation, bending the reinforce portion of the blank to cause it to extend parallel to the wing from which it projects;—thence over the outer surface of the neck, and thence in substantially parallel relation to the other wing, and connecting the free end of the reinforce member to the latter wing.

7. That process of making a slider of the class described which comprises as steps pre-

paring a blank consisting of a unitary piece of sheet metal having front and rear wings united by a relatively narrow neck portion and a reinforce member extending from the free end of one wing, each wing having an opening therethrough, the end of the reinforce member and the free end of the other wing having engageable connecting elements, bending the blank to bring the wings into substantially parallel relation, bending the reinforce member backwardly at its junction with the wing to cause it to extend along said wing, over the neck and substantially to the end of the other wing, and uniting the engageable connecting elements of said latter wing and the reinforce member.

8. That process of making a slider of the class described which comprises as steps preparing a blank consisting of a unitary piece of sheet metal having front and rear wings united by a relatively narrow neck and having a reinforce portion united to one of the wings, bending the blank to bring the wings into substantially parallel relation, and bending the reinforce portion of the blank to cause it to lie substantially parallel to the outer surface of the wing with which it is united and to cause it to extend around the neck and into substantially parallel relation to the outer surface of the other wing.

9. That process of making a slider of the class described which comprises as steps preparing a blank consisting of unitary piece of sheet metal having front and rear wings united by a relatively narrow neck and having a reinforce portion united to one of the wings, bending the blank to bring the wings into substantially parallel relation, bending the reinforce portion of the blank at a point adjacent to its union with the wing to cause it to lie substantially in contact with the outer surface of said wing, and uniting the reinforce device to said wing at a point adjacent to the junction of the latter with the neck, and uniting the reinforce to the free end of the other wing.

10. That process of making a slider of the class described which comprises as steps preparing a blank consisting of a unitary piece of sheet metal having front and rear wings united by a relatively narrow neck and having a reinforce portion united to one of the wings, bending the blank to bring the wings into substantially parallel relation, bending the reinforce portion of the blank to cause it to extend in substantially parallel relation to the wing with which it is united, thence about the neck and in substantially parallel and spaced relation to the other wing, and connecting the end of said reinforce portion to said latter wing adjacent to the free end of the latter.

11. That process of making a slider of the class described which comprises as steps preparing a blank consisting of a unitary piece

of sheet material having wing portions united by a neck, each wing portion having an opening adjacent to its point of union with the neck, and a part extending from the free end of one wing, said part carrying a rivet tab, bending the rivet tab to a position substantially perpendicular to the plane of the blank, bending the blank to bring the wings into substantially parallel relation with the openings in alignment, and bending the part carrying the rivet tab to cause the tab to extend transversely through the opening in the wing to which said part is attached and through the opening in the opposite wing, and so engaging the free end of the tab with the latter wing as to prevent separation of the wings.

12. That process of making a slider of the class described which comprises as steps preparing a blank consisting of a unitary piece of sheet metal having wing portions united by a neck, the wings having apertures therethrough, and an extension projecting from the free end of one wing, said extension carrying a rivet tab, bending the rivet tab to a position substantially perpendicular to the plane of the blank, bending the blank to bring the wings into substantially parallel relation, and bending the extension to cause the rivet tab to project through the openings in the wings.

13. That process of making a slider of the class described which comprises as steps preparing a blank consisting of a piece of sheet material having wings united at one end by a relatively narrow neck, each wing having an aperture at a point adjacent to its junction to the neck, and an extension projecting from one wing, said extension having an aperture therein, a tab projecting inwardly from the edge of the aperture, bending the tab to cause it to extend substantially perpendicularly to the plane of the blank, bending the blank to bring the wings into substantially parallel relation, bending the extension to cause the tab to project through the apertures in both wings, and bending the free end of the tab to prevent its withdrawal.

14. That process of making a slider of the class described which comprises as steps preparing a blank consisting of a piece of sheet material having wings united at one end by a relatively narrow neck, each wing having an aperture at a point adjacent to its junction to the neck, an extension projecting from one wing, said extension having an aperture therein, and a rivet tab projecting inwardly from the edge of said aperture, bending the rivet tab to cause it to project at an angle to the plane of the blank, contracting the extension laterally substantially to close the aperture therein, and bending the blank to cause the wings to assume a substantially parallel relation and to cause the rivet tab to pass through the apertures in both wings.

15. That process of making a slider of the class described which comprises as steps preparing a blank consisting of a piece of sheet material having wings united at one end by a relatively narrow neck, each wing having an aperture at a point adjacent to its junction to the neck, and an extension projecting from one wing, said extension having a large aperture therein and tabs projecting inwardly from opposite sides of the aperture, bending the tabs to cause them to project at substantially right angles to the plane of the blank, contracting the extension laterally substantially to close the aperture and to bring the tabs into engagement, and bending the blank to bring the wings into substantially parallel relation and to pass the tabs through the openings in both wings.

16. That process of making a slider of the class described which comprises as steps preparing a blank consisting of a piece of sheet material having wings united at one end by a relatively narrow neck, each wing having an aperture at a point adjacent to its junction to the neck, and an extension projecting from one wing, said extension having a large aperture therein and tabs projecting inwardly from opposite sides of the aperture, bending the tabs to cause them to project at substantially right angles to the plane of the blank, contracting the extension laterally substantially to close the aperture and to bring the tabs into engagement, bending the blank to bring the wings into substantially parallel relation with their apertures in alignment, bending the extension into substantially parallel relation to one wing thereby to project the tabs through the aligned openings in the wings, and bending the free ends of the tabs in opposite directions.

17. That process of making a sheet metal slider which comprises as preliminary steps preparing a blank having an aperture therein and a tab projecting inwardly from the edge of the aperture, bending the tab out of the plane of the blank, and contracting the blank laterally whereby substantially to close the aperture.

18. That process of making a sheet metal slider of the class described which comprises as preliminary steps preparing a blank having a diamond-shaped aperture therein and having tabs projecting inwardly from the edges of the aperture adjacent to the shorter axis of the latter, bending the tabs to cause them to project substantially at right angles to the plane of the blank, and contracting the blank laterally whereby substantially to close the aperture and thereby to bring the tabs substantially into engagement.

19. That process of making a slider of the class described which comprises as steps preparing a blank consisting of a unitary piece of sheet metal having front and rear wings united by a relatively narrow neck portion

and a reinforce member extending from the free end of one wing, each wing having an opening therethrough, the reinforce member being of lozenge shape and having a central diamond-shaped aperture and tabs projecting from opposite sides of the aperture at its widest part, the tabs being oblique to the axis of the blank and converging toward one another, bending the tabs substantially at right angles to the plane of the blank, contracting the reinforce member laterally substantially to close the aperture and to bring the tabs into contact, bending the blank to bring the wings into substantially parallel relation, bending the reinforce member at its junction and the wing to cause it to lie parallel with the wing and to cause the tabs to project through the openings in the wings, and bending the ends of the tabs in opposite directions.

20. That process of making a slider of the class described which comprises as steps preparing a blank consisting of a unitary piece of sheet metal having front and rear wings united by a relatively narrow neck portion, a reinforce member extending from the free end of one wing, each wing having an opening therethrough, one wing at least having marginal flange portions and the neck having marginal tabs and the reinforce member having a pair of rivet tabs, bending the marginal portions of the wing and the tabs of the neck in the same direction to cause them to extend substantially perpendicular to the plane of the blank, bending the rivet tabs in the opposite direction, bending the blank at the neck to bring the wings into substantially parallel relation with the marginal wing tabs projecting inwardly, and bending the reinforce members to cause the rivet tabs to pass through the openings in the wings and to cause the reinforce member to extend over the neck and down to the free end of the other wing.

21. A blank for use in making a one-piece slider body for use with separable fasteners of the class described, said blank consisting of a unitary piece of sheet material having wing portions united by a relatively narrow neck, an extension united to the free end of one wing, and a rivet member integral with said extension at a point intermediate the ends of the latter.

22. A blank for use in making a one-piece slider body for use with separable fasteners of the class described, said blank consisting of a unitary piece of sheet material having wing portions united by a relatively narrow neck, an extension united to the free end of one wing, and a pair of rivet tabs carried by said extension, said rivet tabs being located between the free ends of the extension and the point of union of the latter with the wing.

23. A blank for use in making a one-piece slider body for use with separable fasteners

of the class described, said blank consisting of a unitary piece of sheet material having wing portions united by a relatively narrow neck, an extension projecting from the free end of 5 one wing, said extension having an opening therein, and a rivet tab extending inwardly from the edge of said opening.

24. A blank for use in making a one-piece slider body for use with separable fasteners 10 of the class described, said blank consisting of a unitary piece of sheet material having wing portions united by a relatively narrow neck, an extension projecting from the free end of one wing, said extension having an opening 15 therein, and rivet tabs projecting diagonally inward, in converging relation, from opposite edges of the opening.

25. A blank for use in making a one-piece slider body for use with separable fasteners 20 of the class described, said blank consisting of a unitary piece of sheet material having wing portions united by a relatively narrow neck, guide tabs projecting from opposite edges of the neck, an extension projecting 25 from the free end of one wing, rivet means carried by the extension, and means at the end of the extension for uniting it to the free end of the other wing.

26. A blank for use in making a one-piece slider body for use with separable fasteners 30 of the class described, said blank consisting of a unitary piece of sheet material having wing portions united by a relatively narrow neck, an extension united to the free end of 35 one wing, said extension terminating in a tongue said extension having a rivet tab substantially midway its length, the other wing having an opening adjacent to its free end for the reception of said tongue, and each 40 wing having an opening near its junction with the neck for the passage of the rivet tab.

27. A blank for use in making a one-piece slider body for use with separable fasteners of the class described, said blank consisting 45 of a unitary piece of sheet material having wing portions united by a relatively narrow neck, and a substantially lozenge-shaped extension united to the free end of one wing, said extension having a diamond-shaped central opening, rivet tabs projecting toward 50 one another at the widest part of the opening, and a connecting tongue projecting from the outer end of said lozenge-shaped extension, said tongue being adapted to engage an 55 opening in the free end of the other wing.

Signed by me at Berlin, Conn., this nineteenth day of April, 1927.

GEORGE E. PRENTICE.
